CORE SIGNALLING DEVICE

Wallace M. O'Reilly and Martin E. True, Houston, Tex., assignors, by mesne assignments, to Esso Research and Engineering Company, Elizabeth, N. J., a corporation of Delaware

Application January 17, 1955, Serial No. 482,023

6 Claims. (Cl. 255—1.4)

The present invention is directed to a device for indicating the taking of a core in a well bore. More particularly, the invention is directed to a core signalling device adapted to be arranged in a core barrel positioned in a drill string. In its more specific aspects, the invention is concerned with a device which signals or detects the taking of a core at the well head.

The present invention may be briefly described as a core signalling device adapted to be arranged in a wire line retrievable core barrel adapted to be arranged in a drill string. The device comprises means carried on the exterior thereof for diverting pumped drilling fluid through the device. A rotatable valve means is arranged in the device in the path of flow of the diverted drilling fluid. Means are connected to the rotatable valve means actuatable by entry of the core in the core barrel which rotates the valve means and decreases the flow of drilling fluid through the device whereby increase in pressure of the pumped drilling fluid signals entry of the core in the core barrel.

The device of the present invention comprises a core cutter, a core barrel, and a core catcher in the core barrel. Initially arranged adjacent the core catcher is a core follower which is attached, by a longitudinally extending means such as a fluted or helical driving rod, to a rotatable valve means arranged in operative relationship to a fixed valve means. The rotatable valve means is an orifice plate having ports adapted to be placed into alignment with ports in the fixed valve means.

The device of the present invention is provided with a packing means on its exterior surface whereby drilling fluid is diverted through the device and through the valve means such that rotation of the rotatable valve means by the core entering the device causes flow of drilling fluid to be interrupted which results in an increase of pressure of the pumped drilling fluid which indicates when a core is being taken.

The present invention will be further illustrated by reference to the drawing in which:

Fig. 1 is an elevational view partly in section of the device of the present invention shown in coring position in a conventional well bore;

Fig. 2 is a front sectional view of the upper portion of the device shown in Fig. 1;

Fig. 3 is a front sectional view of the lower portion of the device shown in Fig. 2;

Fig. 4 is a plan view of the core follower and driving rod of Fig. 2;

Fig. 5 is a plan view of the rotatable orifice plate of Fig. 2;

Fig. 6 is a plan view of the fixed orifice plate of Fig. 2; Fig. 7 is a plan view of the drive collar of Fig. 2; and Fig. 8 is a detail of the latching dog of Fig. 1.

Referring now to the drawing in which identical numerals will be employed to designate identical parts, numeral 11 designates a core barrel provided with a core cutter 12 and adapted with a fishing neck arrangement 13 to permit its use with a wire line. It may be

2

gravitated into position in the lowermost portion of a drill string 14 extending to the earth's surface and connected to a source of drilling fluid being pumped under pressure. The lower end of the drill string 14 has a core bit 14a attached thereto through which the core cutter 12 projects.

The core barrel 11 may be provided with a core catcher 15 comprised of spring members 16 which serve to hold the core, when taken, in the core barrel.

10 Arranged immediately above the core catcher 15 in the passageway 17 of the core barrel 11 is a core follower 18 which is connected to a driving rod 19.

The driving rod 19 is keyed by a guide key 20 which engages with a keyway 21 against rotational movement in the passageway 17. The upper portion of the driving rod 19 is provided on its exterior surface with a fluted, twisted, or helical surface 22 which matingly engages with a surface 23a of a drive collar 23 which is threadably connected by mating threads 24 with an adapter cylinder 25.

15 The upper end 26 of the driving rod 19 is arranged in the passageway 23b defined by surface 23a of the drive collar 23 such that engagement of the surface 22 with the surface 23a causes rotation of the adapter cylinder 25.

20 25 The passageway or chamber 17 is provided with a plurality of relief valves 27 comprised of seating members 28 threadably connected by mating threads 29 into the core barrel 11 and spherical valve members 30 biased onto the seats 31 by helical coil springs 32. The spherical seating members 30 serve to close off the passageways 33 and to open same for discharge through lateral passageways 34 on movement of the guide key 20 and core follower 18 upward in the chamber or passageway 17.

The adapter cylinder 25 is rotationally mounted on 35 ball bearings 35 arranged in bearing retaining rings 36. The upper end of the adapter cylinder 25 is sealed against the inner wall 37 of the core barrel 11 by means of sealing members 38 and 39.

Attached to the upper end of the adapter cylinder 25 40 is a cage member 42 provided with a plurality of ports 43 communicating through lateral passageways 44 with the interior entry chamber 45 of the device and with the annulus A between the device and the drill string 14.

Attached to the upper end 46 of the cage 42 by mating 45 threads 47 is a rotatable valve orifice plate 48 provided with a passageway 49 and sized orifices 50 and 51. The rotatable valve plate 48 is in operative relationship with a fixed valve plate 52 which is threadably connected to the core barrel 11 by mating threads 53. The first valve 50 plate 52 is provided with a passageway 54a of the same size as passageway 49 and with an orifice slot 54.

The core barrel 11 is provided with lateral passageways 55 for diversion of drilling fluid from the annulus A through the valve means. The drilling fluid is diverted 55 through the valve means comprised of plates 48 and 52 by means of a packer such as an upwardly facing cup packer 56.

The core barrel of the present invention may be constructed of a lower section 57 connected to an intermediate section 58 by mating threads 59 which, in turn, is connected to an upper section 60 by a connecting assembly 60a using mating threads 61 and to a top packer section 62 by mating threads 63; it is possible to construct the device integrally. However, it is preferred to construct the device in sections as has been indicated for convenience of assembly and/or maintenance.

Attached to the upper end of the core barrel 11 by 70 mating threads 8 is a latching and retrieving assembly 9 provided with a fishing neck 13 and latching dog 10. The core barrel 11 is retained against upward movement in drill string 14 by means of the latching dog 10 engaging with a recess 7 in the drill string. The latching dog 10

is biased outwardly by a biasing spring 19a and the dog 10 rides against the interior wall of the drill string 14 until the recess 7 is reached at which time it is forced outwardly into the recess to engage therewith.

The device of the present invention operates as follows:

The core barrel 11 is lowered into the drill string 14 until the dog 10 locks the core barrel 11 in the recess 7. Thereafter, as the drill string 14 and the core barrel 11 are rotated, the core, not shown, enters the core barrel through the core cutter as the core barrel 11 moves downwardly over the drive rod 19, the core follower 18 and the core. This causes drive rod 19 to move through the passageway 23b of drive collar 23. The fluted or helical surfaces 22 engage with surface 23a and cause the drive collar 23 and the adapter cylinder 25 to rotate which, in turn, rotates the cage 42. In the meanwhile drilling fluid which is being pumped down the drill string 14 is diverted through passageways 55 by closing off the annulus A by means of pressure exerted against the cup packer 56. The drilling fluid will normally pass through the orifices 49 and 54a, the orifices 50, 51 and 54 in plates 48 and 52. However, rotation of the adapter cylinder 25 and the plate 48 causes a fluctuation in the pressure of the drilling fluid by virtue of alternate placing of the orifices 50 and 51 in alignment with the orifice slot 54. The reduction of free passage of the drilling fluid through the ports 55 and 43 and thence to port 44 to annulus A causes a pressure signal to be transmitted to the well head, not shown. This may be observed visually on the mud pump gauge or may be recorded automatically.

By virtue of the pressure signal, it is possible to tell when a core is entering the core barrel since there is a series of significant changes in pressure only when the core is entering the core barrel. Since entry of the core in the core barrel causes rotation of the plate 48, this signals the core entry and core cutting. Thus the pressure at the earth's surface may be automatically recorded as a plot of mud pressure versus depth or observations of pressure variations will indicate the depth at which cores are or have been taken and when cores are satisfactorily entering the core barrel. For example, the present invention will indicate the taking of cores satisfactorily in increments as small as 1 foot. After the core has been taken the core barrel 11 may be retrieved by engaging a wire line fishing tool with the fishing neck 13 and an upward pull releases dog 10 from the recess 7 allowing the apparatus to be retrieved from the well.

The present invention is quite useful as a core indexing or core signalling device in that it reflects the depth from which cores are taken within predetermined intervals and permits prolonged single coring trips since the coring assembly need not be pulled until it is filled with core samples.

Besides indicating the depth at which cores are taken by pressure fluctuations and besides signalling positively when cores are entering the core barrel, the present invention is quite advantageous in that the core does not come into contact with drilling fluid or drilling mud circulated through the device. Therefore, the present invention is quite advantageous.

The fluctuation in drilling fluid pressures possible in the use of the present invention may be employed to determine the amount and/or length of cores recovered from the various intervals penetrated and precise correlation may be effected with well depth in subsequent core analysis.

The present invention indicates when the core barrel is filled and obviates premature round trips to recover incomplete cores. By round trip is meant going into the hole with the drill string or wire line coring assembly and coming out of the hole with the wire line coring assembly or drill string to remove a drill bit and/or a core barrel.

The nature and objects of the present invention having been completely described and illustrated, what we wish to claim as new and useful and to secure by Letters Patent is:

- 5 1. A core signalling device adapted to be arranged in a retrievable core barrel in a drill string through which drilling fluid is being pumped, said retrievable core barrel being provided with a chamber having an inlet and an outlet providing a path of flow for drilling fluid through 10 the chamber which comprises, packing means carried by said core barrel on its exterior surface for diverting said pumped drilling fluid through said chamber, valve means comprising a fixed orifice plate and a rotatable orifice plate arranged in said chamber in the path of flow of said diverted drilling fluid, and core follower means operatively connected to said rotatable orifice plate, said core follower means being actuated by the core entering said core barrel and said core follower means rotating said rotatable orifice plate and thereby decreasing flow of 20 drilling fluid through said chamber whereby an increase in pressure of the pumped drilling fluid signals entry of the core into the core barrel.
2. A core signalling device adapted to be arranged in a retrievable core barrel in a drill string through which drilling fluid is being pumped, which comprises, said retrievable core barrel provided with a chamber having an inlet and outlet providing a path of flow for drilling fluid through the chamber, an upwardly facing cup packer carried by said core barrel on its exterior surface for diverting said pumped drilling fluid through said chamber, valve means comprising a fixed orifice plate and a rotatable orifice plate arranged in said chamber in the path of flow of said diverted drilling fluid, an elongated member connected to said rotatable orifice plate for rotating 30 said rotatable orifice plate, core follower means connected to said elongated member, said core follower means being forced upwardly by the core entering said core barrel and thereby rotating said elongated member and said rotatable orifice plate and decreasing flow of 35 drilling fluid through said chamber whereby an increase in pressure of the pumped drilling fluid signals entry of the core in the core barrel.
3. A device in accordance with claim 2 in which the elongated member is provided with a helical surface matingly connected to said rotatable orifice plate for rotating said rotatable orifice plate.
4. A core signalling device which comprises a retrievable core barrel provided with a core cutter and having a chamber isolated from the core barrel, said chamber 50 having an inlet and an outlet providing a path of flow for drilling fluid through the chamber, said device being adapted to be arranged in a drill string through which drilling fluid is being pumped, means carried by said core barrel for diverting pumped drilling fluid through said chamber, valve means comprising a fixed orifice plate and a rotatable orifice plate arranged in said chamber in the path of flow of said diverted drilling fluid, and core follower means operatively connected to said rotatable orifice valve plate, said core follower means being 55 actuated by the core entering said core barrel and said core follower means rotating said rotatable orifice plate and thereby decreasing flow of drilling fluid through said chamber whereby an increase in pressure of the pumped drilling fluid signals entry of the core into the core barrel.
6. A core signalling device which comprises, a retrievable core barrel provided with a core cutter and having a chamber isolated from the core barrel, said chamber having an inlet and an outlet providing a path of flow for drilling fluid through the chamber, said device being adapted to be arranged in a drill string through which drilling fluid is being pumped, an upwardly facing cup packer carried by said core barrel on its exterior surface for diverting pumped drilling fluid through said chamber, valve means comprising a fixed orifice plate and a rotatable orifice plate arranged in said chamber in the path 70 of flow of said diverted drilling fluid, and core follower means operatively connected to said rotatable orifice plate, said core follower means being actuated by the core entering said core barrel and said core follower means rotating said rotatable orifice plate and thereby decreasing flow of drilling fluid through said chamber whereby an increase in pressure of the pumped drilling fluid signals entry of the core into the core barrel.
7. A core signalling device which comprises, a retrievable core barrel provided with a core cutter and having a chamber isolated from the core barrel, said chamber having an inlet and an outlet providing a path of flow for drilling fluid through the chamber, said device being adapted to be arranged in a drill string through which drilling fluid is being pumped, an upwardly facing cup packer carried by said core barrel on its exterior surface for diverting pumped drilling fluid through said chamber, valve means comprising a fixed orifice plate and a rotatable orifice plate arranged in said chamber in the path 75 of flow of said diverted drilling fluid, and core follower means operatively connected to said rotatable orifice plate, said core follower means being actuated by the core entering said core barrel and said core follower means rotating said rotatable orifice plate and thereby decreasing flow of drilling fluid through said chamber whereby an increase in pressure of the pumped drilling fluid signals entry of the core into the core barrel.

of flow of said diverted drilling fluid, an elongated member connected to said rotatable orifice plate for rotating said rotatable orifice plate, core follower means connected to said elongated member, said core follower means being actuated by the core entering said core barrel and thereby rotating said elongated member and rotatable orifice plate and thereby decreasing flow of drilling fluid through said core barrel whereby an increase in pressure of the pumped drilling fluid signals entry of the core into the core barrel.

10 6. A device in accordance with claim 5 in which the

elongated member is provided with a helical surface matingly connected to said rotatable orifice plate for rotating said rotatable orifice plate.
